FIG. 1.

INVENTOR

Frank Criest.

BY
Fred G. Dietrich & Co
ATTORNEYS

UNITED STATES PATENT OFFICE.

FRANK CRIEST, OF SHARPSVILLE, PENNSYLVANIA.

WALKING TOY FIGURE.

1,329,959.

Specification of Letters Patent.

Patented Feb. 3, 1920.

Application filed August 13, 1919. Serial No. 317,201.

To all whom it may concern:

Be it known that I, FRANK CRIEST, a citizen of the United States, residing at Sharpsville, in the county of Mercer and State of Pennsylvania, have invented certain new and useful Improvements in Walking Toy Figures, of which the following is a specification.

This invention has reference to toy figures having leg members adapted, when moved along a floor or other base, to assume the walking attitude, and my said invention more especially relates to the type of toy figures disclosed in my copending application filed July 14, 1919, Serial No. 310564.

In the type of toy figure described and shown in my copending application referred to, the structure thereof includes, in connection with a pair of legs, means coöperative with one leg for causing the other leg to kick.

My present form of kicking doll, in the nature of a modified form of the general structure shown in my other application stated, comprehends means coöperative with the body and both legs of the doll whereby either of the legs can be caused to assume a kicking position.

Among other objects, my present invention has for its purpose to provide, in a doll or other figure having a pair of legs in which the legs are relatively so designed and connected with the body part that the walking action is easily attained when moving the toy along a base and the operation of causing either of the legs to kick is effected by a slight downward pressure applied to the body part.

My present invention embodies, in a toy structure of the general character stated, certain features of construction and combinations of parts explained in the following detailed description, as specifically set out in the appended claims and as illustrated in the accompanying drawings, in which:

Figure 1 is a perspective view of a walking doll embodying my invention, the same being shown in a kick-up position.

Fig. 2 is a front perspective view of a manikin form of doll constructed in accordance with my present invention, the parts being shown in the position for effecting the kick-up movement of one of the legs.

Fig. 3 is a diagrammatic face view of the body structure shown in Fig. 2 and illus-

trates a modified connection for causing the leg member to assume the elevated or kick-up position hereinafter explained in detail.

Figure 4 is a detail view, in section, taken on the line 4—4 on Fig. 3.

In the doll structure disclosed in my copending application referred to, the legs are individually hinged directly to the body part and the means coöperative with one of the legs for causing the other leg to rise to a kicking motion is such that only one leg of the doll can be shifted to assume the high kicking position.

In my present construction of doll both legs are connected with the body and to each other in such manner that as the "doll" is sustained with the downward pressure applied on one leg, the relatively upward movement of the stationarily held leg with respect to the downwardly moving body is transmitted to the other leg to effect a downward movement of the said other leg relatively to the downwardly moving body. Again, in my present construction of doll, each leg has a hinge or hip joint connection and each leg also has an attached connection that joins therewith below the hinge pivot and with the body part, and which operates, as the leg is being forced in the downward direction, to swing the hinged member to the kick-up position.

In my present form of walking and kick-up doll, the same comprises, generally, a body part 1, which in practice may be a block of wood suitably shaped to represent the body of a doll or other walking figure.

As is best shown in Figs. 2 and 3, each leg 2 is hinged to a block 30 on the lower end of a rod-like extension 3 and the said rods are guided in elongated bearing apertures 4, 4 in the lower part of the body 1, and in sockets 5, 5 in the upper part of the said body.

The front of the body 1 is cut out to produce a transverse socket 6 that provides for exposing portions of the rods or legs extensions 3, and for conveniently and economically applying a cross connection 7 between the said extensions 3, 3 whose purpose is to impart movement in reverse directions to the legs relatively to each other and to the body movement, as will be presently more fully explained.

The connection 7 mentioned, is in the nature of a rocker that is centrally pivoted, as

at 70, to the body 1, between the opposing leg extensions 3, 3. The outer opposite ends of the rocker member 7, which, as shown, are adapted for swinging in the vertical direction, are projected through elongated slots 5 31—31 in the extensions 3, 3, as shown.

In the arrangement of the parts so far described and as shown in the drawing it will be readily understood that the connection of the legs and body part are such that 10 as the body is pushed or pulled along over a suitable base and exerting a slight downward pressure on the body (see, for example, arrow *x* Fig. 2) as the body thus moves 15 downwardly the pivoted connection 7 is caused to rock in the direction of the arrow *y* (see Fig. 2) and thereby cause the other leg to move downwardly with respect to its companion leg and somewhat faster than the 20 speed of movement of the body and although both the body 1 and the said other leg are moving in the downward direction stated, the block 30 of the said other leg will move away from the lower edge of the said body.

25 In my present construction of walking doll it is the said apparent downward motion of the legs, with respect to the body, that is utilized for assisting in the kick-up, or swinging action of the legs.

30 The aforesaid results are obtained either by a cross connection, as shown in Fig. 2, or by the modified form of connection shown in Fig. 3, the latter being the cheaper and more easily applied way of effecting the kick-up or leg swing. In Fig. 35 2, the cross connection comprises a pair of wires 8, 8, one end of each of which is connected to its respective leg at a point below the hinge joint and the said wires 8, 8 40 cross and extend upwardly over the body portion.

The upper ends of the wires 8, 8 each slidably engage a guide 9 secured and movable with the leg extensions 3, 3.

45 The cross connection, the wires 8, 8, is such that so soon as downward motion is transmitted to one leg the wire connecting it with the upper end of the extension 3 of the other leg being now held taut and from 50 slidable engagement with its guide 9, operates to lift the leg to which it is attached and cause it to swing to the kick-up position, the swiftness of the kick depending on how quickly down pressure is applied to 55 the body 1. It is obvious that either of the legs can be readily selected for doing the kick-up act.

While the wire connections 8, 8 are of a stable or serviceable character for the more 60 expensive grade of walking dolls, for the cheaper grade of toy doll the hinged legs may be connected directly to the lower end of the body by elastic cords 10, 10, one end of each of which is made fast to the body 65 and the other end attached to the legs be-

low their hinged joints, as clearly shown in Fig. 3.

The cords operate to effect the kick-up of their respective legs in the same manner that the wire connections 8, 8 operate, except 70 that the cords do not cross over and are connected, each to the body 1, directly over the connection with their respective leg members.

Either of the connections 8, 8 or 10, 10 75 constitute, as it were, a flexible fulcrum or pivot for the legs to which they are connected below their hinge pivots and by reason thereof, as the block 30 of the extensions 80 of the leg that is to swing up moves downwardly the hinge leg portion is swung up, the connections 8^a or 10^a and their co-operating cords 10 or wire 8 constitute means tending to swing the hinge leg member up as the extension 3 and the block 30 are 85 moved downwardly through action of the cross or rocker member 7.

From the foregoing description taken in connection with the accompanying drawings, it is thought the complete construction, the manner of its use and the advantages of my present invention will be 90 readily understood.

What I claim is:

1. A walking toy comprising a body, a 95 pair of articulated legs carried by the body, both of the said legs having up and down movement relatively to the body and connections between the two legs and the body whereby as either leg is held stationary and downward pressure is applied to the body the other leg has a kick-up movement imparted to it, the said connection including leg extensions and a rocking element pivotally mounted on the body whose opposite 100 ends loosely engage the leg extensions of the pair of legs.

2. A walking doll comprising a body, a pair of hinged legs telescopically connected with the body and means co-operative with 110 the legs for causing either leg to kick up as the other leg is held down and downward pressure is applied to the body.

3. A walking doll comprising a body, a pair of articulated leg elements carried by 115 the body, both of said leg elements having telescopic movement relatively to the body and connections between the two leg elements and the body whereby as either of the leg elements is held stationary the other leg element will have a kick-up motion imparted to it, the said connections including a rocking element pivotally mounted on the body and having its opposite ends loosely engaging the said pair of leg elements.

4. A walking doll comprising a body, a pair of oppositely disposed members each telescopically engaging the body and projected at the lower end below the body, a leg hinged to the lower end of each of the

telescopic members, and means connecting the legs and the body, for causing the leg attached to the member that moves downwardly to kick up as the body is slid downwardly to kick up as the body is slid downwardly on the other leg attached member.

5. A walking toy of the character described, comprising a body, a pair of uprights each including an upper extension, a leg portion hinged to the lower end of each 10 of the said upper extensions, the said extensions forming supports upon which the body is slidably mounted, means coöperative with the body and the two upper extensions adapted to impart a downward movement to one extension as the other is held rigid and the body is moved downwardly thereon, and means connecting the hinge members of the legs with the body whereby to cause the leg of the upper member 15 being forced downward to kick up

under the downward pressure of the body as it slides down on the other upright or leg member.

6. A walking toy figure that comprises a pair of uprights each including a hinged 25 leg member, a body mounted upon and having vertical movement on the uprights, means coöperative with the body and the opposite pair of uprights adapted for projecting one of the said uprights downwardly with but in advance of the body as the leg is forced to move down along the other upright, and other means engaging the hinged leg members and the body whereby, as the upright is being downwardly advanced 30 with the downwardly forced body, the leg-member of the said advancing upright is caused to kick up.

FRANK CRIEST.
